ELECTRICAL PLUG PRONG

Ben Degaetano, 1 Megan Lane,
Armonk, N.Y. 10504

Filed Mar. 9, 1973, Ser. No. 339,577

Term of patent 14 years

Int. Cl. D13—03

U.S. Cl. D26—1 A

FIG. 1

FIG. 2

FIG. 3

FIG. 1 is a perspective view of the electrical plug prong showing my new design;

FIG. 2 is a bottom plan view thereof; and

FIG. 3 is a side elevational view thereof.

I claim:

The ornamental design for an electrical plug prong, as shown.
